N. G. BRITTON

DEVICE FOR PLUGGING OIL WELLS

Filed Oct. 18, 1927

Nathan Goff Britton Inventor

By Watson E. Coleman Attorney

UNITED STATES PATENT OFFICE.

NATHAN GOFF BRITTON, OF NEWBERNE, WEST VIRGINIA.

DEVICE FOR PLUGGING OIL WELLS.

Application filed October 18, 1927. Serial No. 226,961.

This invention relates to devices for plugging oil wells and has for an important object thereof the provision of a device of this character which will provide an effective 5 and thorough seal of the well.

As is well known to those familiar with the art, oil well plugs have hitherto been of two different types. The first and most commonly employed type is a rubber plug 10 which, when inserted in the well, is expanded against the walls of the casing to provide the necessary seal. The second is a soft metal plug which is expanded by a mandrel. Each of these types is possessed of faults 15 which render it impractical. The rubber packer has a tendency to deteriorate after being in the well a short time and if there is any substantial gas pressure, will be blown out or the deterioration will result in 20 leakage. The soft metal plug, while affording when expanded sufficient resistance to prevent blowing out, is not capable of producing an absolutely tight seal, so that there is always a small seepage or pressure leak 25 thereabout. Accordingly, an important object of the present invention is the provision of a plugging structure which will not leak or blow out and accordingly provides a permanent seal for the well.

30 These and other objects I attain by the construction shown in the accompanying drawings, wherein for the purpose of illustration is shown a preferred embodiment of my invention and wherein:—

35 Figure 1 is a vertical sectional view through well plugging apparatus constructed in accordance with my invention showing the parts in the position which they occupy when the device is lowered into the 40 well;

Figure 2 is a similar view showing the parts in their operative or packing position.

Referring now more particularly to the drawings, the numeral 10 generally designates the bottom of a well bore and 11 a 45 casing arranged within the bore. In accordance with my invention, I provide a tube 12, the lower end of which is sealed and adapted for engagement with the well bottom 10, being preferably made relatively heavy, as illustrated. Secured within this tube are a plurality of bent spring fingers 13 having their upper outer ends secured to the tube wall, as at 14, and their inner free 50 ends 15 arranged at different levels within

the tube. The upper end of the tube threads into an annulus 16 having an upstanding flange 17 upon which is seated the lower end of a rubber packer 18. This rubber packer has a bore 19 for the reception of 60 a tapered mandrel 20 and the lower end of this mandrel is provided with an extension 21 having upwardly facing teeth 22 behind which the terminal portions 15 of the springs 13 are adapted to engage when the 65 mandrel is forced downwardly through the rubber packer to expand the same.

The upper end of the mandrel 20 has a recess 23 receiving a reduced extension 24 formed on the lower end of a soft metal 70 plug 25. This soft metal plug 25 has attached thereto by a readily frangible or bendable pin 26, the lower end of a tapered mandrel 27, the upper end of which is adapted for engagement with a means for 75 lowering the same into the well, as indicated at 28.

In the use of the device, the tube 12 is made of such length that the packer will be 80 properly spaced from the lower end of the well, and the entire assemblage is lowered into the well until the lower end of this tube seats upon the well bottom 10. Pressure is then applied from above, forcing 85 the mandrel 20 downwardly until the rubber packer has been so firmly engaged with the walls that the resistance resulting will be sufficient to enable the mandrel 27 to release its anchoring means and move downwardly through the soft metal plug 25 to expand the same into engagement with the 90 walls of the casing. While the anchorage afforded by the metallic packing would, in most instances, prove sufficient to prevent dislodgment of the mandrel 20, this mandrel is locked in its lowered position by the 95 engagement of the spring fingers 15 with the teeth 22 of its extension 21. Thus, both the lead plug and latching means serve to hold the packer 18 against vertical displacement in the well bore and the packers mutually serve to reinforce one another. In order to anchor the lower end of the mandrel 20 to the plug structure during lowering operations, the extension 21 of the mandrel is preferably provided with a head 29 seating about the edges of the opening of the annulus through which the extension passes when the tube 12 is moved downwardly a predetermined distance. The 100 105 110

55 ends 15 arranged at different levels within

above structure may be employed for plugging either oil or gas wells or dry wells in which no oil or gas has been found.

Since the construction hereinbefore set forth is capable of a certain range of change and modification without materially departing from the spirit of the invention, I do not limit myself to such specific structure except as hereinafter claimed.

10. I claim:—

1. A well plug comprising a seat, a rubber packer supported thereby, a member engaged with the seat at its upper end and adapted to engage the lower end of a well bore, with its lower end, a mandrel directed through the rubber packer and limited in its upward movement with relation to the seat, a soft metal packer seated upon the upper end of the last named mandrel and a further mandrel engaging the upper end of the soft metal packer.

2. A well plug comprising a seat, a rubber packer supported thereby, a member engaged with the seat at its upper end and adapted to engage the lower end of a well bore, with its lower end, a mandrel directed through the rubber packer and limited in its upward movement with relation to the seat,

30 seat, a soft metal packer seated upon the upper end of the last named mandrel and a further mandrel engaging the upper end of the soft metal packer, said member and the first named mandrel having coacting means preventing return movement of the first named mandrel when it has been forced 35 downwardly through the rubber packer.

3. A well plug comprising a seat, a rubber packer supported thereby, a member engaged with the seat at its upper end and adapted to engage the lower end of a well bore with its lower end, a mandrel directed through the rubber packer and limited in its upward movement with relation to the seat, a soft metal packer seated upon the upper end of the last named mandrel, a further 40 mandrel engaging the upper end of the soft metal packer, said member comprising a tube sealed at its lower end, spring fingers secured at their upper ends to the walls of the tube and having inward lower ends and 45 an extension for the first named mandrel having upwardly facing teeth for engagement by the lower ends of said springs.

50 In testimony whereof I hereunto affix my signature.

NATHAN GOFF BRITTON.
